UNITED STATES PATENT OFFICE

JOHN K. ODIN, OF NEW YORK, N. Y., ASSIGNOR TO LESHER, WHITMAN & CO., INC., OF NEW YORK, N. Y.

CURTAIN FIXTURE FOR USE IN CONNECTION WITH SHADE BRACKETS

Application filed May 31, 1930. Serial No. 457,707.

This invention relates to curtain supports and more particularly to types in which two longitudinal strips of curtain material are used on the same support and which are adjusted edgewise towards or from each other as may be desired.

One of the several objects is to provide a curtain support rod having terminals adapted to engage in the ordinary type of shade roller brackets, and they are therefore readily available in all windows in which shades have been used without changing the brackets, or marring the frames to which they are attached; an object particularly desirable in all cases, and necessary where steel framed windows are to be curtained.

A further feature is in the provision of means for adjusting the space between the curtain edges, that is easy and positive in operation.

Another object is to arrange the curtains so that the support rod and associated metallic elements are completely obscured.

These objects are accomplished by the novel construction and combination of few and simple parts hereinafter described and shown in the accompanying drawings, forming a material part of this disclosure, and in which:—

Figure 1 is a front elevational view of a conventional type of common window, showing an application of the invention, the curtain being in a closed position, and broken away at its upper corners to show the fixtures.

Figure 2 is a front view of the support rod with its novel terminals engaged in the usual type of shade support brackets.

Figure 3 is a transverse sectional view taken on line 3—3 of Figure 2.

Figure 4 is a similar sectional view taken on line 4—4 of Figure 2.

Figure 5 is a side view of a modified form of rod terminal.

A complete window frame is shown in Figure 1 composed of a sill 10, sides 11 and lintel 12, all of the usual construction.

Fixed near the tops of the inner surfaces of the sides 11 are roller shade brackets 13 and 14, the former having a raised, dome-

shaped face containing a single circular aperture, which in some cases may be open at the top to receive the round pintle of the roller.

The opposite bracket 14 is similarly dome-shaped to contain an elongated aperture, open at the top and front by a slot to receive the flattened pintle of a roller, all these elements being old and of well known construction.

The invention includes a rod or tube 15, straight throughout, preferably of circular cross section and of a length compatible with its purpose.

Fixed on one end of the rod 15 is a cap or socket 16, its closed outer end being formed into a pintle 17 suited to seat in the aperture of the bracket 13, and terminating in a raised bead 18 to prevent the pintle from being withdrawn by axial movement.

Formed on the cap 16 is an outstanding forked member 19 between the prongs of which is journaled a pulley 20 mounted to freely rotate, the pulley and its fork extending preferably in advance of the end of the cap, which may be secured on the rod 15 by a set screw 21, or the parts so proportioned as to constitute a tight fit, in which case no screw is required.

At the opposite end of the rod 15 is secured another cap 22, provided or not with a set screw 21 and having a flattened pintle 23 to seat in the bracket 14, and the pintle may terminate in a bead 24.

Extending at a right angle from the inner end of the cap 22 is a double fork 25 between the tines of which are journaled pulleys 26 and 27.

The curtain material 28 is cut to extend in two strips the full height of the window space and looped at its upper edge to permit the rod 15 to pass freely therethrough.

A cord 29, having tassels 30 at its ends, is trained over the pulleys 26 and 27 to loop around the pulley 20, the doubled portion of the cord extending adjacent the rod 15 through the curtain loops, one of the runs of the cord being attached, as at 31, to the inner edge of the curtain strips and the other run secured, as at 32, to the adjacent edge of the mating strip.

Thus it will be seen that upon pulling one

of the cord ends or tassels, the curtain strips will be drawn towards the frame sides of the window, while pulling the other cord end, the strips may be brought closely together.

5 In the modified form of the device, shown in Figure 5, both of the caps may be plain, as at 33, one having a flat pintle 34 and the other a plain cylindrical pintle.

In this case no cord is used, the curtain strips being moved by hand in the direction desired.

Although I have described my improvements with considerable detail, and with respect to certain particular forms of my invention, I do not desire to be limited to such details since many changes and modifications may well be made without departing from the spirit and scope of my invention in its broadest aspect.

20 Having thus described the invention, what is claimed as new and desired to secure by Letters Patent, is:

1. In a device of the kind described in which a rod is supported at its ends in an opening for the purpose of supporting curtains in said opening, a cap for one end of said rod, said cap provided with an outer end formed into a pintle, said pintle adapted to be seated in the aperture of a bracket secured to one side of said opening and terminating in a raised bead to prevent said pintle from being withdrawn from said bracket by axial movement.

2. In a device of the kind described the combination with a bracket having a dome shaped protuberance with an elongated aperture, of a cap for the end of a curtain rod, said cap provided with an outer end formed into a pintle, said pintle adapted to be seated in the aperture of said bracket and terminating in a raised bead to prevent said pintle from being separated from said bracket by axial movement.

3. In a device of the kind described in which a rod is supported at its ends in an opening for the purpose of supporting curtains in said opening, a cap for one end of said rod, said cap enclosing and adjustably secured to the end of said rod and provided with an outer end formed into a pintle, said pintle adapted to be seated in the aperture of a bracket secured to one side of said opening, a double fork on said cap extending at an angle therefrom and pulleys journaled between the tines of said double fork.

In testimony whereof I have hereunto affixed my signature.

JOHN K. ODIN.
